DISPLAY AND SHIPPING CABINET

Fridolin Schimmel, Faribault, Minn.

Application April 6, 1934, Serial No. 719,278

7 Claims. (Cl. 206—45)

My present invention relates to an extremely simple and highly efficient display and shipping cabinet intended for general use but especially well adapted for holding packets of flour and 5 vegetable seeds.

The primary object of this invention is to provide a display and shipping cabinet with doors or cover sections that may be used as a closure for the open top of the cabinet when the same is being shipped or stored or that may be used as legs for supporting the cabinet at the desired elevation when said cabinet is used for displaying the contents therein.

To the above end, generally stated, the invention consists of the novel devices and combinations of devices hereinafter described and defined in the claims.

In the accompanying drawing, which illustrates the invention, like characters indicate like parts throughout the several views.

Referring to the drawing:

Fig. 1 is a perspective view of the improved cabinet with its cover sections closed;

Fig. 2 is an end elevation of the improved cabinet;

Fig. 3 is a perspective view of the cabinet with the cover sections partly open;

Fig. 4 is a perspective view of the invention when used as a display cabinet and also fragmentarily showing in the cabinet trays for holding packets of seeds as diagrammatically illustrated by means of broken lines;

Fig. 5 is a fragmentary view with some parts sectioned on the line 5—5 of Fig. 4, on an enlarged scale;

Fig. 6 is a fragmentary detail view with some parts sectioned on the line 6—6 of Fig. 1, on an enlarged scale; and

Fig. 7 is a fragmentary detail view with some parts sectioned on the line 7—7 of Fig. 4, on an enlarged scale.

The cabinet includes a rectilinear box-like body 8 that is relatively shallow and has an open top. Said cabinet further includes a pair 45 of doors or cover sections 9 and 10 which, when closed, rest on the upper edge of the body 8 in endwise spaced relation. Hinges 11 connect the cover sections 9 and 10, one to each of the ends of the body 8, for swinging movement from closed 50 positions to complete open positions in which they depend vertically outwardly of the ends of the cabinet and afford legs that support said cabinet at a convenient elevation for the inspection of the contents therein. The cover section 9 55 is bifurcated, at its outer end portion, and the

prongs thereof are designated by the numeral 12 and the outer end portion of the cover section 10 is in the form of a relatively wide tongue 13 that fits between the prongs 12 and forms a close joint therewith as well as the two cover sections 5 9 and 10.

When the cover sections 9 and 10 are closed the prongs 12 rest at their outer end portions on metal plates 14 rigidly secured to the cover section 10 and the tongue 13 rests at its outer end 10 on a like plate 15 rigidly secured to the cover section 9. The two cover sections 9 and 10 when closed are held closed by machine screws 16 which extend through holes in said sections and have threaded engagement with the plates 15 14 and 15. When the cover sections 9 and 10 are positioned to afford legs for the cabinet they are held open by the screws 16 which extend through holes in the cover sections 9 and 10 and have screw-threaded engagement with metal plates 20 17 rigidly secured to the ends of the body 8.

From the above description of the cover sections 9 and 10 it is evident that the novel manner in shaping said sections permits the formation of each thereof to a length considerably greater 25 than one-half of the length of the body 8 so that the cover sections 9 and 10 when used as legs are of the proper length to support the cabinet at the desired elevation.

As shown in Figs. 4 and 5, a plurality of trays 30 18 are removably mounted on a pair of laterally spaced upright supports 19. These supports 19 extend from the front to the rear of the body 8 and are removably mounted in grooves 20 formed in the sides of the body 8. The upper 35 end portions of the supports 19 are shaped to form step-like notches 21 which rise progressively from the front to the rear of the cabinet. The trays 18 extend longitudinally of the body 8 and they loosely rest on the notches 21 which support said trays, the one behind the other, and also slightly one above the other from the front to the rear of the cabinet. Said notches 21 also hold the trays 18 slightly rearwardly inclined.

The trays 18 are transversely divided to form 40 compartments 22 for holding packets X of different kinds of seeds. Obviously, the novel way in which the trays 18 are supported from the cabinet hold the packets X so that the titles thereof may be easily read.

When shipping the improved cabinet the supports 19 are laid flat on the bottom of the body 8 and the trays 18 placed thereon with the packets X therein below the upper edge of said body 50 so that the cover sections 9 and 10 may be closed.

The closing of the cover sections 9 and 10 over the packets X holds said packets in the respective compartments 22 so that they can not get out of place during shipping of the cabinet.

5. To set up the cabinet the cover sections 9 and 10 are opened, turned into leg-supporting positions and secured by the screws 16, as previously described. After the cabinet is set up the trays 18 are removed therefrom as well as the uprights 19 and said uprights placed in the grooves 20 and thereafter the trays 18 are placed on said supports.

10. From what has been said, it will be understood that the cabinet described is capable of modifications as to details of construction and arrangement within the scope of the invention herein disclosed and claimed.

15. What I claim is:

1. In a cabinet of the class described comprising a box-like body having an open top, and a pair of cover sections for said open top hinged one to each end of the body for movement from closed positions to depending positions outwardly of the end of the body, one of said sections being 20 longitudinally bifurcated at its outer end portion and the other of said sections having a tongue-like outer end portion that fits between the prongs of the bifurcated section when the cover sections are closed, said two cover sections having the 25 same longitudinal length.

2. The structure defined in claim 1 which further includes a fastening device for detachably connecting the two cover sections together.

3. The structure defined in claim 1 which further includes a stop member on the bifurcated 30

cover section between the prongs thereof and on which the tongue-like outer end of the other cover section rests when the cover sections are closed.

4. The structure defined in claim 1 which further includes a stop member on the bifurcated cover section between the prongs thereof and on which the tongue-like outer end of the other cover section rests when the cover sections are closed, and fastening means for securing said 35 tongue-like outer end to the stop member.

5. The structure defined in claim 1 which further includes a pair of stop members on the cover section having the tongue-like outer end and on which stop members the prongs of the other cover member rest when the cover sections are closed.

6. The structure defined in claim 1 which further includes a pair of stop members on the cover section having the tongue-like outer end and on which stop members the prongs of the other cover member rest when the cover sections are closed, and fastening means for securing said prongs to the stop members.

7. In a cabinet of the class described comprising a box-like body having an open top, a pair of cover sections for said open top hinged one to each end of said body for movement from closed positions on the body to depending positions outwardly of the ends of the body, said cover sections when closed being edgewise overlapped in the same plane, and means for securing the cover sections to the ends of the cabinet when in said depending positions.
